UNITED STATES PATENT OFFICE

2,023,072

OIL BURNER

John J. Harman, Newton, Mass., assignor to Walworth Patents Inc., Boston, Mass., a corporation of Massachusetts

Application October 12, 1931, Serial No. 568,285

4 Claims. (Cl. 158—73)

This invention relates to oil burners for domestic heaters and particularly to oil burners of the steam atomizing type.

The usual type of oil burner now in common use in domestic heaters operates on the air atomizing or air vaporizing principle and is a complicated and expensive structure ordinarily requiring a motor, a blower or spinner, fans, pumps, spark plugs, intricate electrical devices and gas pilot lights, and has many moving parts, all of which greatly increase the expense of manufacturing and operating the oil burner, and which parts are often out of order and require lubrication, cleaning and repair. The electrical equipment also often causes annoying radio interference. These objections and drawbacks are avoided in large part in an oil burner operating on the steam atomizing principle, but while many attempts to build such burners have been made, they have not been successful for domestic heating.

The chief difficulty has been the proper regulation of the steam supply, such as keeping it at a proper pressure as not to blow out the flame and obtaining a steam of sufficient uniform dryness to properly atomize the oil, and not flood the burner with water to extinguish the flame. Another difficulty has been that previous steam atomizing oil burners have also required extensive installation of equipment, and close attention to steam, water, air and oil supplies, and consequently did not provide the simple and compact structure, and automatic regulation of the various operating factors essential in a successful domestic heater.

An object of the present invention therefore is to provide a practical, efficient and economical burner operating on the steam atomizing principle, suitable for domestic and industrial use and burning a low cost fuel.

A further object is to provide an oil burner of the aforesaid type which consists of a simple compact unit, inexpensive to make, install and operate, free from intricate mechanical devices, and whose parts would ordinarily need no cleaning or repair, but would be quickly accessible if such were necessary, and thereby to avoid expensive repair and maintenance costs.

A further object of the invention is to provide an oil burner completely automatic in operation and which shall require very little or no attention from the owner after once starting it.

An important feature of the invention is its method or principle of operation which consists

in maintaining the steam supply substantially constant while varying the oil supply thermostatically in accordance with the heat demands of the house, and automatically varying the amount of air necessary for most efficient combustion.

Another important feature of the invention lies in its responsiveness to heat demands through gradual modulation of the flame, and within a short range, as required, rather than through the extreme of having too much flame and completely shutting it off.

A further feature of the invention lies in the provision of an effective water feeding device, whereby the flow of water to the steam generator may be accurately controlled and regulated and whose parts will not deteriorate and require constant replacement, the successful operation of any steam atomizing oil burner in large part depending on the efficiency of the water feeder.

A further feature of the invention lies in the automatic safety trip valve for shutting off the supply of oil should the burner cease to operate at any time and thereby to prevent flooding of the burner or cellar with oil.

Other objects of the invention will become apparent from the following description taken in connection with the accompanying drawings, wherein:—

Fig. 1 is a side elevation of an oil burner partly in section embodying the invention.

Fig. 2 is a plan view of the same.

Fig. 3 is a front elevation, partly in section, taken on the line of 3—3 of Fig. 1, looking in the direction indicated by the arrows.

Fig. 4 is a section taken on the line of 4—4 of Fig. 2 looking in the direction indicated by the arrows, and

Fig. 5 is a section taken on the line of 5—5 of Fig. 1 looking in the direction indicated by the arrows.

Referring more particularly to the drawings, the oil burner is shown therein as comprising a plurality of units such as the base plate A, the water feeder B, the ignition chamber C, the nozzle housing D, the combustion chamber E, the steam generator F, and the safety trip valve unit G for the fuel line.

The base plate A is preferably of sheet metal and, in contour, conforms in general to the shape of the units it supports. The base plate may be secured to the floor by means of the leg 10 shown in Fig. 1.

The water feeder B (Figs. 1, 2 and 3) which is

the subject matter of an independent and co-pending application, is mounted on the plate A at the front end thereof and consists of a cup shaped body 15 having its open end closed by a cover 16. A lead gasket 37 may be interposed between the cover 16 and the body 15 and the cover secured by means of screws 38. The lower closed end of the body 15 extends through a base 18 secured to the base plate A and is provided with an outlet pipe 19 connected to the steam generator F.

Formed integrally with the feeder body 15 adjacent its upper end is a lateral hollow projection 17 carrying a valve body 23. The valve body 23 is provided with a valve seat 25 with which a valve member 26 cooperates to control the flow of fluid through an aperture 21 in the seat. The valve member 26 is provided with a stem 28 having spaced webs 29 thereon engaging the interior of the valve body 23 for positioning the valve therein.

Water is conveyed to the valve from a suitable source of supply by means of the pipe 20 connected to the valve body 23 by means of the union 21 and nut 24. Preferably a filter plate 22 is interposed between the valve body 23 and the union 21, as shown in Fig. 3. In order to maintain a desired quantity of water in the feeder the valve stem 28 is connected to a lever arm 32 pivoted on a pin 33 and carrying a float 34 positioned in the body 15 of the feeder.

On the opposite side of the body 15 from the valve is a threaded boss 35 which carries a pipe 62 connected at its opposite end to the steam chamber of steam generator F. In this manner steam is conveyed into the water feeder B for equalizing the pressure between feeder B and generator F.

Mounted on the cover 16 of water feeder B is a steam pressure gauge 39 and a pressure relief valve 40. A pipe 40a leads from the relief valve to carry excess steam through the heater door plate 48 and exhaust it into the domestic heater.

The relief valve 40 is preferably of the weighted type so that it may be set to exhaust at certain pressures by merely adding or subtracting a weight such as two and one-half pounds in winter and one and one-half pounds in spring or early fall. The valve will relieve all excess steam whenever the pressure reaches the desired amount. Preferably the valve is designed to operate as accurately as possible to maintain a desired pressure, and eliminate fluctuations on either side of the desired pressure. Tri-cocks 41 may be mounted on the body 15 at different levels for testing the water levels in the feeder.

A vacuum breaker is provided for the feeder B and comprises a pipe 42 connected to the body 15 at a point below the water level therein. The pipe projects upwardly outside the feeder preferably fifteen feet or more and has its upper end open to the atmosphere. A column of water is carried in this pipe and any vacuum created in the water feeder will draw the water from the pipe, thus breaking the vacuum. It has been found in operation of the burner that when the flame goes out and the water feeder cools the steam in the feeder condenses creating a suction. The objectionable feature is that the suction draws oil through the steam nozzle to clog the water feeder. Hence, if the vacuum in the feeder is not permitted to rise high enough no oil can be drawn through the steam nozzle.

The ignition chamber C, Figs. 1 and 4, for the burner nozzle comprises a cylindrical body

45 positioned beyond the water feeder B and secured to the base plate A preferably by welding. One end of the chamber C is closed by a detachable cover plate 47 carrying the steam and fuel nozzle housings D and provided with holes 5 through which the steam and oil supply pipes project. The other end of the housing C is closed by the heater door plate 48 which takes the place of the door of the domestic heater H. An opening 49 is provided in the door plate 48 to allow 10 passage of the flame therethrough from the burner nozzle. The housing C is further provided with a lighting port normally closed by a cover 50.

A starting oil pan 51 is provided in the bottom of the housing C for receiving oil dripping from the burner nozzle. The oil pan 51 is partially filled with oil and provided with a braided asbestos wick which may be lighted to provide a starting flame for the burner. An overflow pipe 15 20 leads from the side of the oil pan 51 intermediate the top and bottom thereof to carry off surplus oil to the safety valve unit G to be later described.

Opening into one side of the housing C is a 25 draft tunnel or flue 52 which may be lined with felt 53 to muffle combustion noise.

A steam nozzle 55 and oil nozzle 56 are secured to the nozzle housing D. The steam nozzle 55 comprises a pipe having an extending 30 lower lip onto which the oil nozzle 56 is adapted to drop oil. The steam nozzle is positioned centrally of opening 49 in door plate 48 to direct the flame through combustion chamber E into the heater H.

The combustion chamber E (Fig. 1) is a longitudinal passage which confines the burning gases and directs them on to the steam generator F. The combustion chamber as shown is separated from the housing C by the heater door plate 48 40 and its interior is preferably lined with a refractory material 57. At the rear end of the combustion chamber is mounted the steam generator F.

The steam generator F, (Figs. 1 and 5) consists of a water leg 60 of rectangular cross-section 45 disposed centrally across the rear end of the combustion chamber E. The lower end of the water leg 60 is connected to water pipe 19 leading from the water feeder B and is supplied with water therefrom. Surmounting the water leg 60 is a 50 steam chamber 61 into which steam rises. Preferably the steam chamber 61 is partly exposed to the flame in the combustion chamber to superheat the steam therein and thus insure the dry steam essential for proper combustion.

Leading from the upper side of the steam chamber 61 through the heater door plate 48 and connected to the water feeder B is a pipe 62. In this manner the steam pressures in the steam chamber 61 and water feeder B are equalized. 60 Steam is supplied to the steam nozzle 55 by means of a pipe 63 leading from the pipe 62. Preferably, the pipe 62 is arranged so that it slopes from steam chamber 61 to the water feeder B and the steam pipe 63 is carried upwardly 65 before descending to the steam nozzle, thus tending to prevent any condensate from passing back to the steam chamber 61 or entering the steam pipe 63.

Fuel, such as oil, is supplied to the nozzle 56 70 through pipe 65 as previously described. The supply of oil is thermostatically controlled, as shown in Fig. 2, by a valve 66 mounted on the pipe 65 and controlled by a lever 67 connected by a chain 68 to the thermostat T. The thermo-

stat may be of any suitable type but is preferably one that regulates gradually through a narrow range without sudden change. A sediment trap (not shown) may be interposed in the pipe 65 to insure the delivery of oil free from impurities to the burner nozzle.

The safety trip valve unit G operates to shut off the fuel supply, if for any reason the burner has failed to operate. The outlet pipe 70 is connected to oil pan 51 into which unconsumed oil flows from the oil nozzle and overflows into said outlet pipe 70 which opens downwardly into an oil trip pan 71. Preferably outlet pipe 70 is goose-necked to prevent any flames passing therethrough into the oil trip pan 71 and igniting the oil therein.

The oil trip pan 71 is mounted on a pan holder 72 which depends from one end of a lever 73. The lever 73 is balanced on a yoke 75 extending upwardly from the base A and has a counterweight 74 on its opposite end. An ear 76 is provided at the pan end of the lever 73 and engages a latch 77 which is tilttable and carries a weight 78. Connected to the latch 77 and rotatable thereby is the stem 79 of a valve 80 which is mounted on the fuel pipe 65 at a point beyond the valve 66. When sufficient oil overflows into oil drip pan 71 the lever 73 is unbalanced, latch 77 is disengaged and turns valve stem 79 which operates to close valve 80 and shut off the oil supply.

The burner is preferably operated in the following manner:

The fire is started by lighting the asbestos wick in the oil pan 51 and steam is quickly generated. The steam passes to the steam nozzle 55 adjacent the oil nozzle 56 where it atomizes the oil dropping therefrom and the atomized mixture is ignited by the flame in the oil pan.

The flame is directed through the combustion chamber E by the steam jet and the induced draft to the steam generator F. In passing into the fire box of the domestic furnace the flame heats the air of a hot air system or the water in a hot water or steam system. The steam generated in the generator F is carried around to the steam nozzle 55 where it atomizes the oil thereby completing the cycle.

The principle on which the burner operates is that the water delivered to the steam generator is kept at a constant level by the float controlled valve in the water feeder and the steam delivered to the steam atomizer is kept at an unusually low pressure by the relief valve. The amount of steam pressure normally maintained depends upon the oil consumption of the burner. In a burner such as that shown in the drawings having an oil consumption range from one-sixth to two gallons per hour the relief valve is set at one or one and one-half pounds at the lower rate of consumption and at two and one-half or three pounds at the higher rate. On larger installations, such as apartment houses or hotels where larger quantities of oil are burned per hour a higher constant pressure up to say five pounds will naturally be required. It is desired to operate on as low a steam pressure as will atomize the oil properly and keep the burner and heater clean.

The amount of oil delivered to the nozzle and consequently the heat produced is controlled by the thermostat operating the valve in the fuel pipe. The amount of air necessary for efficient combustion is automatically provided at all times by the natural induction effect of the steam jet

and flame, which varies with the amount of fuel supplied.

There is thus no fluctuation in the steam pressure which heretofore has ranged from 1 to 15 lbs. and which was continually blowing out the flame at higher pressures when a small amount of fuel was being consumed and which was so difficult to control. With the unusually low constant steam pressure disclosed herein this difficulty is eliminated and adequate heat to maintain a desired house temperature is available at all times.

The fuel supply by this method is not turned on and then completely off as in other methods. The burner is operated continually but the oil consumption is not greater than in other burners for the reason that the heat requirements are maintained by burning the minimum amount of oil rather than by burning an excessive amount part of the time and then shutting the burner off completely. The low steam pressure used does not create the objectionable combustion noise so apparent in burners operated by other methods and using higher steam pressures. Hence, all the objects of the invention have been accomplished.

What is claimed is,

1. A liquid fuel burner of the class described, comprising a substantially cylindrical housing closed at one end, the opposite open end of said housing being adapted to project within a furnace, a positioning flange intermediate the ends of said housing adapted to be secured to and position said housing with respect to said furnace, a steam generator positioned adjacent the open end of said housing, a burner unit supported by said housing adjacent the closed end thereof for receiving steam from said generator and discharging it in a jet, said burner being spaced from the generator leaving a combustion chamber therebetween, means for supplying fuel through the housing to said jet to be atomized, a starting fuel pan forming part of the housing beneath the burner, and a draft tunnel opening into one side of the housing rearwardly of said burner with respect to the combustion chamber.

2. A liquid fuel burner of the class described, comprising a housing, a fuel atomizing device in said housing, a fuel supply connected to said atomizing device, a steam generator, means connected to said atomizing device and generator for supplying steam under low pressure to atomize the fuel said housing having, an air inlet rearwardly of the atomizing device with respect to the generator and supplying air for combustion by the inductive action of the atomizing device, a relief valve connected to the steam supply means to maintain the steam within a predetermined low pressure range, a control valve for the fuel supply and a thermostat connected to said valve to vary the supply of fuel to vary the heating capacity of the mixture of air, fuel and steam.

3. A liquid fuel burner of the class described, comprising a housing adapted to project partly within a furnace, a steam generator positioned at the end of the housing within the furnace, a fuel atomizing unit in the housing adjacent the opposite end thereof receiving steam from said generator and discharging it in a jet toward the generator, and means for supplying fuel to said steam jet to be atomized, said housing having an inlet for air in one side thereof rearwardly of said atomizing unit, the part of the housing between

the steam generator and the atomizing unit constituting a combustion chamber within which substantially complete combustion occurs.

4. A liquid fuel burner of the class described, comprising a housing adapted to project partly within a furnace, a steam generator positioned at the end of the housing within the furnace, a fuel atomizing unit in the housing adjacent the opposite end thereof receiving steam from said generator and discharging it in a jet toward the 10 generator, means for supplying fuel to said steam

jet to be atomized, said housing having an inlet for air in one side thereof rearwardly of said atomizing unit, the part of the housing between the steam generator and the atomizing unit constituting a combustion chamber, and means in said housing beneath the atomizing unit for igniting the mixture of air, fuel and steam, said mixture undergoing substantially complete combustion in said combustion chamber before reaching the generator. 5

JOHN J. HARMAN.
